United States Patent Office

Des. 214,464
Patented June 17, 1969

214,464

SCALE

William Macowski, Montclair, N.J., assignor to Ketcham
& McDougal, Inc., Roseland, N.J., a corporation of
New Jersey

Filed June 4, 1968, Ser. No. 12,198

Term of patent 14 years

Int. Cl. D10—08

U.S. Cl. D52—10

FIG. 1

FIG. 2

FIG. 3

FIG. 4

FIG. 5

FIG. 1 is a perspective view of a scale showing my new design with the weighing platform shown in dotted lines for illustrative purposes only;

FIG. 2 is a top plan view thereof;

FIG. 3 is a side elevational view thereof;

FIG. 4 is a rear elevational view thereof; and

FIG. 5 is a front elevational view thereof.

I claim:

The ornamental design for a scale, as shown and described.
